UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

ELECTRICALLY-CONTROLLED FEED MECHANISM.

No. 886,294.

Specification of Letters Patent.

Patented April 28, 1908.

Application filed February 28, 1906. Serial No. 303,453.

To all whom it may concern:

Be it known that I, BENGT M. W. HANSON, a citizen of Sweden, who have declared my intention of becoming a citizen of the 5 United States, residing at Hartford, in the county of Hartford and State of Connecticut, have invented certain new and useful Improvements in Electrically-Controlled Feed Mechanism, of which the following is a 10 specification.

This invention relates to electrically controlled devices for regulating the movement of feed-mechanism, and while illustrated applied to means which may be employed for 15 determining the true cylindricity of work is limited to no special art, being in many of its details applicable for use in various classes of machines.

Mainly, the object of the invention is the 20 provision of improved contact-devices, governed by what is technically known as a "feeler" in engagement with the work, and serving to control automatically the feed-motion of the machine.

25 Further objects of the invention relate to details of the contact-devices, and to improved electrical connections, plugs, etc. whereby mistakes due to carelessness may be avoided.

30 Other objects of the invention will be disclosed in the now-following, detailed description.

In the accompanying drawings Figure 1 is a view in elevation, showing part of an automatic feed-mechanism, and electrically-controlled devices for controlling the movement of the same. Fig. 2 is a transverse section of a machine-bed, a cross-slide mounted on ways thereof, and a casing carried by said 35 slide, parts being shown in elevation. And Fig. 3 is a front view of the parts illustrated in Fig. 2 detached from the way of the machine on which they are placed.

Like numerals designate similar parts 45 throughout the several views.

Referring to Fig. 1 of the drawings, the numeral 1 designates a shaft of mechanism (not shown) which may operate the means for feeding a reducing-tool or other implement, and rigid with said shaft is a ratchet-wheel 2, only a part of which is illustrated.

Adjacent to the ratchet-wheel and supported to swing freely upon the hub thereof is a pawl-bearing arm 3, in which near its

hub is firmly fitted a wrist-pin 4 passing 55 through a slot 5 in the end of a link 6, having a reciprocating motion due to a connection at its other end (not shown) with any suitable device. When driven forward the link 6 will first take up lost-motion with reference 60 to arm 3 in consequence of the slot 5 moving over pin 4 until the end of the slot engages with said pin 4, and swings the arm 3 through an arc due to the amount of advance of said link 6.

Pivoted on a screw of arm 3 is a pawl 8, having a ratchet-engaging tooth 9, and held to its work by a spiral-spring 10, one end of which is attached to a pin 11 on said pawl 8, and its other extremity to a pin 12 on arm 3, 70 as shown by dotted lines in Fig. 1. Attached at 13 to the outer end of pawl 8 is an armature 14, the electro-magnet 15 of which is supported on an extension 16 of arm 3.

Designated by 17 is a spring attached at 75 its lower end to extension 16, and provided at its opposite extremity with a latch 18. When the pawl 8 is raised to disengage tooth 9 from ratchet-wheel 3 by a handle 19 at the free end thereof or the magnet 15 is energized to accomplish this result, the latch 18 snaps over a corner of the armature 14 and retains it in said position.

Beneath the extension of arm 3, and in contact with the under side thereof is a vertically-adjustable screw 20, having a rounded tip 21 and a knurled head 22, said screw being threaded into a lug 23 of a plate 24. This plate is to be attached to the machine-frame by screws 25 and dowels 26, and pivoted at 27 to this plate is a lever 28, carrying in an internally-threaded boss 29 of its upper end a vertically-adjustable stop-screw 30, having a knurled head 31; the smooth shank of said screw just clearing the outer end of the extension 16. Attached to an intermediate part of lever 28 is an armature 32, and connected at one end to a stud of a lug 33 of lever 28 is a coiled spring 34, said spring bearing at its opposite extremity against a lug 35 of the plate 24.

Designated by 36 is an electro-magnet secured to the plate 24, the base of the solenoid 37 of which is attached to the said plate 24, the parts being located in an inclined position, as illustrated. When magnet 36 is energized the angular inward movement of lever 28 is sufficient to throw the end of stop-

screw 30 under the extension of arm 3 when said arm is swinging to advance the pawl, and on the return movement of said arm and pawl the arc of traverse will be limited by 5 said stop-screw and according to the position in which it is set. By providing the slot 5 in link 6 a sufficient amount of lost-motion is permitted to enable the constant reciprocatory travel of said link, and also to permit 10 the arm 3 to have its arc of movement limited in the manner described.

Designated by 38 and 39 are battery-cells for supplying the necessary current to energize the magnets 15 and 36 when the proper 15 contacts and connections are made. These battery-cells may be located at any convenient point in or about the machine in which the feed-mechanism is employed.

Referring to Fig. 2, the numeral 40 indicates the way of a machine-frame in the base of which the batteries 38 and 39 may be located, and on which may be placed the usual head-and tail-stocks (not shown) carrying the live and dead-centers for supporting the rotating work 42, with which in the present instance, the invention coöperates.

A chambered base 43 is adjustably clamped to the way 40, in any desired manner, and in said way is a longitudinal T-slot 44, in which 30 is inserted an L-shaped clamp 45 for readily applying and detaching the dimensioning apparatus hereinafter described.

In a transverse bore of the base is mounted a shaft 46 having a reduced eccentric-portion 35 47 at one end on which the clamp 45 is sleeved, and a handle 48 at its opposite extremity. A nut 49 secures the clamp against displacement longitudinally of the shaft, and a spring-actuated plunger 50 mounted in a socket of 40 the base 43 bears with constant pressure against the threaded end of the shaft upon the eccentric part of which said nut is mounted. To permit the removal of the dimensioning apparatus the shaft 46 is turned 45 to release the clamp, and then by thrusting the shaft inward the base and its parts may be readily withdrawn by an upward movement, the clamp moving through the slot.

No claim is made in this application to the 50 improved clamping-devices for they constitute part of the subject-matter of my application filed Sept. 8, 1905, Serial Number 277,549.

Fitted in a transverse guideway 51 on the 55 top of the base 43 is a slide 52, perforated at its outer end to receive a nut 53, which is secured by a screw 54. In said nut is threaded a screw 55 supported in a bracket 56 secured to the end of an overhang 57 of the base 43 by 60 screws 58. On the outer end of the screw 55 is splined a hand-wheel 59 prevented from displacement by a nut 60, and on the hub of said hand-wheel is sleeved a graduated ring or micrometer gage 61 which will coöperate 65 with the usual mark (not shown) on the top

of bracket 56 to indicate the advance of slide or carriage 52.

Mounted on the slide 51 is a supporting frame or casing 62, and in the inner end of this casing is pivoted an angle-lever 63, having a short arm 64 carrying a split-clamp 65 in which a pin 66 acting as a "feeler" to engage the work 42, is secured. In the free end of the long arm of said lever a screw 67 having a knurled head 68 and a contact-point 69 is threaded. At its rear end the casing is provided with a cover 70 hinged at 71 and having a lifting-knob 72. Rising from the base of the casing 62 are separated standards 73, but one of which is shown in Fig. 2, and in the upper ends of said standards is journaled a rock-shaft 74. Rigid with this rock-shaft 74, and secured thereto at about its central portion, is a lever 75 having a weighted arm 76 to over-balance 85 its arm 77. In a socket at the end of the arm 77 is secured a plug 78 of platinum or other suitable metal shaped to form a contact-point at its lower end. A pin 79 on one of the standards prevents the descent of the 90 weighted arm 76 beyond a certain point.

Journaled in the standards 73 diagonally below the rock-shaft 74 is a second rock-shaft 80, and secured intermediate its ends to the rock-shaft 80 is a lever 81, having a 95 weighted arm 82 and a forwardly-projecting arm 83. In a socket at the free end of arm 83 a bushing 84 composed of insulating material is inserted, and in said bushing is located a platinum or other plug 84' shaped at 100 its ends to form contact-points. Below the plug 84 and located in a socket of the casing is a bushing 85, also of insulating-material, and in said bushing is a metallic plug 86 having a contact-point 87 at its upper end 105 adapted to engage the contact point of the plug 84.

From the rock-shaft 80 an arm 88 depends, and threaded into the base of the casing is a screw 89 having a knurled head 90, 110 the point of said screw engaging said arm, and the screw serving to adjust the lever 81 as circumstances may require.

Designated by 91 is a rock-shaft which is journaled in the sides of the casing, and carries at a point beneath the long arm of the lever 63 a pin or tappet 92, and at its end exterior to the casing a handle 93 by which the lever 63 may be actuated to force its long arm upward and its short arm to the right to 120 discharge the feeler 66 from the work.

Disposed along the front of the machine-bed are two series of sockets 94 and 95, the sockets of each series being spaced apart from each other for a purpose hereinafter 125 described. In the sockets 94 insulating plugs or bushings 96 are threaded, while in those indicated by 95 other insulating-plugs or bushings 97 are secured in the same manner.

Each of the bushings 96 and 97 is internally threaded to receive externally-threaded, hollow plugs 98, 99 respectively, the bore of each of which is tapered; that of the plug 98 being larger than that of the bore in the plug 99. Removably fitted in the taper-bore of the plug 98 is the tapered shank of a pin 100, and similarly fitted in the bore of the plug 97 is the tapered shank of a plug 101 of less diameter than said pin 100. It is frequently necessary to break the circuit, and to avoid any possible mistake in reestablishing the same the tapered shanks of the pins are made of different sizes. It is, of course, impossible to insert the larger pin in the end of the tapered bore of the plug 99, and should the smaller pin be inserted in the larger bore of the plug 98 the connection will not be established, and when the fingers are released it will, due to the tapered surfaces of the pin and bore, immediately either fall out of the bushing or be inclined to an innocuous position. Connecting the pins 100 are insulated wires 102 and connecting the pins 101 are like wires 103, each wire being conveniently disposed along the side of the frame of the machine, or located in grooves for their reception along said side.

Connected to the shank of the right-hand end pin 100 is a wire 104 leading to binding-post on the positive pole 105 of the battery-cell 38, and attached to another of said pins 100, to all of the series of which the wire 102 is connected as stated, is a wire 106 leading to a binding-post 107 mounted in an insulated bushing 108 fitted in an opening of the casing 62. Leading from said binding-post 108 to the plug 84 is a wire 109, and also leading from the plug 77 is a wire 110, in contact with the metallic casing 62, which for the purpose of conductivity is a part of the machine-frame.

Connected at one end to the plug 86 is a wire 111 attached at its opposite extremity to a contact-post 112. A wire 113 leads from said contact-post to the shank of the plug 101, and through the wire connection 103 to the shank of the last plug 101 of the series, from which the wire 114 leads to the positive pole of the battery 39. To the negative-pole of said battery a wire 115 is attached, said wire leading up to, and being in contact with, the solenoid magnet 15. A wire 116 is attached at one end to the negative-pole of the battery 38, and at its opposite end to the solenoid magnet 36. In this way the circuit from the batteries is established, and, supposing the machine to be utilized in connection with the reduction of work by a grinding process, the operation is as follows—

Before the action of the dimensioning apparatus commences the work to be reduced is placed on centers of the usual head and tailstocks, said stocks being carried by a reciprocating carriage, the feed mechanism of which

actuates said carriage and traverses the work along the surface of a reducing-agent not shown.

To illustrate the manner in which the apparatus works, attention is invited to Letters Patent granted to me June 30, 1903, Number 732,184 to which reference may be had. At the inception of the operation of the present invention the rock-shaft 91 is turned to lower its projection 92 out of engagement with the long arm of lever 63, thereby permitting said arm to fall by gravity, and to carry its shorter arm 64 inward, and cause an engagement of the feeler 66 with the work to be reduced. As said work traverses the reducing-agent the feeler, of course, closely follows its surface, and when the work has been reduced to the desired extent the contact-screw 67 will engage the plug 69. As further reduction occurs in the diameter of the work, said screw 67 will force downward the weighted lever 76, and cause the contact-plug 84 to then engage both of the plugs 69 and 86, thereby establishing a circuit through the wires and connections described to the electro-magnet 15, energizing the solenoid thereof, and drawing down the lever 8 until it is locked by the latch-lever 17. This stops the feed, and indicates that the work is finished. When contact with the plug 84 is made by point 69 the circuit is established between said plug 84, the wire 109, contact 107, wire 106, plugs 100, wire 103, wire 104, and battery 38 with the wire 116, thereby energizing the magnet 36, and causing the lever 28 to be swung inward on its pivot 27 against the action of the spring 34 to throw the end of the screw 30 beneath the extension 16 of lever 3, thus limiting the descent of said lever and in case too much reduction has taken place altering the stroke of the feed-arm 3, and of the pawl in engagement with the ratchet-wheel 2. In this way and by adjusting the screw 30 the descent of arm 3 is adjustably limited, and as said arm carries the pawl 8 the stroke of said pawl will be varied according to the adjustment of said screw 30 and the feed consequently regulated in accordance with the amount of reduction desired. After complete reduction has taken place, new work has been inserted, and an additional operation is to be performed, the pawl 8 is released by the means described and the tooth 9 thereof again engages the ratchet-wheel 2, and the circuit being broken spring 34 will swing the pivoted lever 28 carrying the screw 30 back to normal the position illustrated in Fig. 1. To vary the feed of the ratchet-wheel 2 connected with the feed-mechanism of the reducing-tool the screw 20 is adjusted, and the point of said screw will limit the descent of lever 3, and thus regulate the advancing movement of the same and accordingly governing the feed. When new work is to be

inserted the rock-shaft 91 is turned to throw the feeler 66 away from the path of the same, and by grasping the handle on the end of the spring latch 17 and moving said latch to the right, it is released from locking engagement with the pawl 8, and the point 9 of said pawl is then caused to engage the ratchet-wheel 2 by the spring 12, thus placing the parts in condition for a renewal of the operation.

10 Micrometric adjustment of the slide 52 carrying the feeler and the various devices described is provided for by turning the screw 55. Should it be desired at any time to disestablish the circuits prevailing through 15 the connections described from the batteries, this may be readily accomplished by removing any of the plugs 100, 101, from the contact bushings 98, and 99, and as before stated it will be impossible to establish the circuit 20 unless the right plugs are placed in the bushings having openings of different diameters for their reception.

Changes may be made in various details of the mechanism without departure from the 25 spirit thereof, and while shown applied for use to a metal reducing machine the invention is limited to no special use, nor to employment with any particular material.

Various means may be employed for 30 clamping the base 43 to the reciprocating bed 40, the invention not being limited to the devices described. So too, other means may be utilized for raising the lever carrying the feeler and various kinds of contact-devices 35 may be employed as substitutes for those shown if desired.

Having thus described my invention, what I claim is—

1. The combination, with a feeler adapted 40 to engage work to be reduced, of a movable device on which the feeler is mounted; a contact-point carried by the device; levers pivoted beyond said contact-point; contact-plugs carried by said levers; feed-mechanism; an electric-circuit; and means for disconnecting said feed-mechanism when the said circuit is established.

2. In mechanism of the class described, the combination, with a pivoted angle-lever, 50 of a feeler carried by one arm of said angle-lever; a contact-point carried by the other arm of said angle-lever; movably-mounted devices having plugs; an electric-circuit; a support having an insulated contact-point 55 adapted to engage one of the contacts of said movable devices; feed-mechanism; means for actuating said feed-mechanism; and electrically-controlled devices for withdrawing the means for actuating the feed-mechanism.

60 3. The combination, with a slide, of an angle-lever pivoted to said slide; a feeler carried by one arm of the angle-lever; a contact-point carried by the other arm of said angle-lever; a support; weighted levers pivoted to said support; contact-points carried

by said weighted levers; a contact-point carried by the support; feed-mechanism; means for operating said feed-mechanism; an electric-circuit; and means for throwing out of action the operative element of the feed-mechanism when the electric-circuit is established.

4. The combination, with an angle-lever, 75 of a contact-point carried by one end of said lever; a feeler carried by the other end of said lever; a pivoted lever; a contact-device carried by said pivoted lever; an electric-circuit; a feed-element; and means controlled by the electric-circuit when the contact-point of the angle-lever engages the contact-device of said pivoted lever for controlling said feed-element.

5. The combination, with a feeler, and 80 with means for movably supporting the same, of a contact-point carried by said means; a pair of pivoted levers; a contact-device carried by each of said levers; a circuit; a feed-element; and means controlled by the circuit for actuating said feed element.

6. The combination, with a swinging arm, 90 of a pawl carried by said arm; a feed-element actuated by said pawl; a stop movable beneath an extension of said arm; and electrically-actuated devices for operating said stop.

7. The combination, with a ratchet feed-element, of a swinging arm; a pawl carried by said arm, and engaging the ratchet feed-element; an electro-magnet for withdrawing the pawl; and means for throwing the pawl into engagement with the ratchet feed-element 100 when the magnet is deenergized.

8. The combination, with a feed-element, and with means for actuating the same, of a stop for limiting the movement of said feed-element, and electrically-controlled devices 105 for actuating said stop.

9. The combination, with a feed-element, and with a swinging support, of means carried by the support for engaging said feed-element; a stop movable beneath the support; a pivoted lever carrying said stop; and means for actuating said lever.

10. The combination, with a feed-element, and with a swinging support, of means carried by the support for engaging said feed-element; a stop movable beneath the support; a pivoted lever carrying said stop; an armature carried by said lever; and a magnet for actuating said lever.

11. The combination, with a feed-element, 120 and with a swinging support, of means carried by the support for engaging said feed-element; a stop movable beneath the support; a pivoted lever carrying said stop; an armature carried by said lever; a magnet for actuating said lever; and a spring for returning said lever.

12. The combination, with a carrier, of a feeler on said carrier; a pair of contact-points, one carried by the lever; a support 130

for the other contact-point; an electric-circuit; a feed-element; a device for actuating said feed-element; an electro-magnet in the circuit; and a stop movable beneath an element of the device for actuating the feed-element, and controlled by said electro-magnet.

13. The combination, with a ratchet feed element, of a swinging arm; a pawl carried by said arm; an electro-magnet carried by the arm for withdrawing the pawl; a circuit for energizing the magnet; and a catch for retaining the pawl when disengaged from the ratchet feed-element.

14. The combination, with a support, of an angle-lever pivoted thereto, and one arm of which is longer than the other; a feeler carried by the short-arm of said angle-lever; a contact point mounted in the long arm of said angle-lever; a pivoted lever; a contact-point carried by said pivoted lever; an electric-circuit; feed-mechanism; and means actuated by said circuit for controlling the action of said feed-mechanism.

15. The combination, with a support, of an angle-lever pivoted thereto, and one arm of which is longer than the other; a feeler carried by the short arm of said angle-lever; a contact-point mounted in the long arm of said angle-lever; a pivoted lever; a contact-point carried by said pivoted lever; an electric-circuit; feed-mechanism; means actuated by said circuit for controlling the action of said feed-mechanism; a second-circuit; means for establishing said second-circuit at a predetermined point; and means controlled by said second-circuit when established for throwing the feed-mechanism out of action.

16. The combination, with a slide, and with means for adjusting the same of an angle-lever pivoted to the slide; a feeler carried by one arm of said angle-lever; a contact-point carried by the other end of said angle-lever; a pair of pivoted levers; a contact-point carried by one of said levers, and electrically-connected with part of the slide; an insulated contact-point carried by the other pivoted lever; electric-circuits; feed-mechanism; means actuated by one electric-circuit, when established for regulating the movement of said feed-mechanism; and means actuated by the establishment of the other electric-circuit for stopping said feed-mechanism.

17. The combination, with a pivoted angle-lever having long and short arms, of a contact-point carried by the long arm of said lever; a feeler carried by the other arm of said lever; electric-circuits; mechanisms controlled by the contact-point on the angle-lever for establishing said circuits; and feed-mechanism controlled and thrown out of action by the respective circuits.

18. The combination, with a shaft, of a ratchet-wheel secured thereto; a swinging

arm mounted on the shaft adjacent to said ratchet-wheel; a pawl carried by said swinging arm, and having a tooth engaging said ratchet-wheel; a slotted connection for actuating the swinging arm; an electro-magnet carried by a part of the arm; means for energizing said magnet; an armature carried by the pawl; and a latch for locking the pawl when its tooth is withdrawn from the ratchet-wheel.

19. The combination, with a shaft, of a ratchet - wheel mounted thereon; an arm sleeved upon the shaft adjacent to the ratchet-wheel; a pawl carried by said arm; and a slotted connection for actuating said swinging-arm.

20. The combination, with a shaft, of a ratchet-wheel rigid therewith, a lever sleeved upon the shaft adjacent to said ratchet-wheel; a wrist-pin carried by the lever; a pawl pivoted to the lever; and a reciprocatory rod slotted at its end to receive the wrist-pin.

21. The combination, with a shaft, of a ratchet-wheel actuated thereby; an arm mounted for swinging movement upon the shaft; a wrist-pin carried by the arm; a reciprocatory rod having a slot in which the wrist-pin is received; a pawl carried by the arm; and means for regulating the feed-movement of said arm.

22. The combination, with a feed-element, of a swinging arm; means carried by said arm for actuating said feed-element; and a stop movable beneath the arm, and adjustable to limit the motion of said arm.

23. The combination, with a feed-element, of an arm mounted for swinging movement; means carried by the arm for actuating the feed-element; a lever; an armature on said lever; an adjustable stop carried by the lever; an electro-magnet coöperating with the armature, and adapted to throw the adjustable stop beneath a portion of the swinging arm, and thus limit the feed-movement.

24. The combination, with a ratchet-feed element, of a swinging arm; a pawl carried by said arm, and in engagement with said ratchet feed-element; an armature carried by the pawl; an electro-magnet coöperating with the armature to withdraw the pawl; and a latch for engaging the armature, and holding the pawl out of contact with the ratchet-feed-element.

25. The combination, with a ratchet-feed-element, of a swinging arm; a pawl carried by said arm, and in engagement with said ratchet feed-element; an armature carried by the pawl; an electro-magnet coöperating with the armature to withdraw the pawl; a latch for engaging the armature, and holding the pawl out of contact with the ratchet-feed element; and a spring for returning the pawl when the latch is released.

26. The combination, with a ratchet feed-

element, of a swinging arm; a pawl pivoted on said arm, and engaging said ratchet feed-element; an armature carried by the pawl; a spring-latch for engaging the armature; an 5 electro-magnet carried by the swinging-arm; and a circuit for energizing said magnet, and thereby releasing the pawl from contact with the ratchet-feed-element.

27. The combination, with a ratchet-feed-10 element, of a swinging arm; a pawl carried by said arm; a pivoted lever; a stop adjustable on said lever; an armature carried by the lever; an electro-magnet for attracting the armature when energized; and a circuit 15 for energizing said magnet, and thus throwing the adjustable stop beneath a part of the swinging arm to control the feed-movement.

28. The combination, with a ratchet feed-20 element, of a shaft carrying said element; an arm sleeved upon the shaft adjacent to said element; a pawl pivoted to the arm; means for holding the pawl in contact with said element; an armature carried by the pawl; an 25 electro-magnet; a circuit for energizing said magnet; means for locking the pawl out of engagement with the feed-element; a pivoted lever; a stop on said lever; an armature also carried by the lever; an electro-magnet for attracting said armature; a 30 circuit leading to said magnet; and means for

returning said pivoted lever and adjustable stop.

29. The combination, with a shaft, of a ratchet feed-element carried by said shaft; an arm sleeved upon the shaft adjacent to 35 said feed-element; means for actuating the arm; a pawl pivoted to the arm; an extension on the arm; an adjustable stop located beneath said extension; a pivoted lever; means for actuating said lever; and an adjustable stop carried by the lever, and adapted to be thrown beneath the extension of the 40 arm to limit the movement of said arm.

30. The combination, with a shaft, of a ratchet-feed-element carried by said shaft; 45 an arm sleeved upon said shaft; a pawl carried by the arm, and in engagement with the ratchet-feed-element; an armature carried by the pawl; an electro-magnet located on a portion of the arm beneath said armature; 50 means for energizing the magnet to cause it to withdraw the pawl from engagement with the feed-element; and a latch for said means.

In testimony whereof I affix my signature in presence of two witnesses at Hartford, 55 Conn., this 16th day of February, 1906.

BENGT M. W. HANSON.
